UNITED STATES PATENT OFFICE.

RICHARD IRVIN, OF KNOXVILLE, PENNSYLVANIA.

GARAGE STRUCTURE.

Application filed August 14, 1926. Serial No. 129,114.

My invention relates to garages and other structures to which vehicles have access, and which contain a plurality of floors or stories arranged at successive heights. The objects in view are increased facility in moving vehicles to and from any particular point in the building; this together with maximum capacity for storing automobiles or other vehicles within minimum limits of ground area and height of building.

This application is in part a continuation of an application filed by me February 4, 1926, Serial No. 85,926.

A garage or storage building of my invention is illustrated in the accompanying drawings. Fig. I is a view in horizontal section through the building; Fig. II is a view in longitudinal section, on the plane indicated at II-II, Fig. I; and Fig. III is a view in transverse section, on the plane III-III, Fig. I. Fig. IV is a fragmentary view to larger scale, on the plane indicated at IV-IV, Fig. I and showing diagrammatically a detail of structure.

The floor surface of this structure, from ground to roof, is essentially obliquely helicoidal in its extent, but the shape is modified and departs from a true oblique helicoid in these particular respects: first, the helicoid is developed, not on a single axis, but on a plurality of axes, and preferably, and as here illustrated, on two axes. Referring to Fig. I of the drawings, the floor surface there seen in plan is developed about two vertical axes, whose positions are indicated at D and B. To one side, to the right of a vertical plane extending medially through the structure and defined by the axes D and B (the helix is left-handed, the ascent being in counter-clockwise direction), the helicoid is developed on B as the center of the generatrices; to the other side, to the left of that vertical plane, the helicoid is developed on the center D.

A second modification of the obliquely helicoidal shape lies in this, that the change from one of the axes to the other as the center for the generatrices, occurs, not in the medial vertical surface defined by the axes D and B, but in a plane radial with respect to the new center, which the rising helicoid meets somewhat in advance of the plane D B. In Fig. I of the drawings I have indicated by the lines D E and B F vertical planes in which the change indicated takes place. The helicoid rising to the right of

plane D B is developed upon the axis B, up to the plane D E. There the center shifts from B to D and the helicoid continues to develop on D as a center until the plane B F is reached, and there the center shifts again. These planes D E and B F are subtended by the rising spiral somewhat in advance of the plane defined by the axes D and B. The purpose of this refinement in structure will presently be indicated.

A third modification of the obliquely helicoidal shape lies in this, that the angle of obliquity changes at successive points in the course of the development of the helicoid. The generatrices form with the axis of development at successive points in the development angles of different value. That is to say the angle of the banking of the floor changes in the course of the rise of the floor.

In a fourth respect the floor in its form departs from a typical oblique helicoid. In its extent outward from the axis of generation, the obliquity changes; the floor outwardly approaches more nearly a right helicoid, that is to say, a helicoid whose generatrices extend perpendicularly to the axis of development. Stated in other words, the floor is warped outwardly toward the horizontal.

A fifth modification of the helicoid is that the pitch varies, being alternately of increased and of diminished gradient.

The floor includes an inner portion which constitutes a ramp, for the ascent and descent of vehicles, and an outer portion which constitutes storage areas. The conditions which limit dimensions are, first, that there shall be head room between successive turns of the helicoid; second, that the ramp area shall be such in size and pitch as to allow cars to be moved up and down upon it with proper freedom; and, third, that the obliquity of the ramp, that is to say its inclination transversely shall be such as to afford greatest facility in moving cars up and down upon it. In city regions, where the problem of finding areas for automobiles at rest is most urgent, land is of greatest value, and it becomes necessary to build garages for storage on ground areas of minimum extent. My invention is a solution of the problem, and affords upon a minimum ground area, maximum storage area per floor combined with greatest freedom of movement of cars from floor to floor.

The drawings show a particular building in which the features which I have indicated are actually embodied. Referring still to Fig. I, I would indicate first the rectangle A B C D and then, surrounding that, the rectangle M N O P. The floor areas defined between those two rectangles is the inner, ramp portion, of which I have made mention. The ramp ascends in continuous (though irregular) helicoid from the ground to the highest floor; it is approximately rectangular in plan, with opposite reaches 1 and 2 and intervening opposite reaches 3 and 4. The outermost dimensions of this ramp portion are in this particular building 85 by 90 feet, and, throughout the straight-away portions of its course, the ramp is in the clear 25 feet wide. I find it convenient to form the gradient portions 3 and 4 at 9 per cent and the gradient portions 1 and 2 at 4 per cent.

The ramp is banked transversely; that is to say, inclined upwardly from its inner to its outer edge, and the degree of inclination in the banking is suited to the normal curved course of a car as it runs along the ramp in ascent or descent. This transverse inclination is greatest at the corners, in the regions A—M, B—A, C—O, and D—P, and is least 25 midway along the rectangular sides. In short, my ramp is so built that cars may travel it with greatest expedition, considering the limited areas within which the cars must be handled. The gradient of the reaches 1 and 2 is in Fig. III indicated by the line a—b; and the gradient of the reaches 3 and 4 is in Fig. II indicated by the line c—d. The banking of the ramp across the reach 2 is in Fig. II indicated by the line 30 d—e.

On either side of the helicoidal ramp and continuous with the ramp, throughout the reaches 1 and 2 extend the successive floors 5 and 6. The floors 6 it will be perceived 45 alternate in height with the floors 5, and the floors of each series rise in vertical succession with head room between. In this particular installation then the ramp is extended along reaches 1 and 2 in floors 5 and 6; but in reaches 3 and 4 is closed in by adjacent walls, with the consequence that the building is of elongate rectangular plan, as best seen in Fig. I. But, as will readily be understood, reaches 3 and 4, as well as 50 reaches 1 and 2, might be made longer and of reduced gradient, and floors might extend from them also. Indeed, the successive floors 6, 5, etc., may be considered as fragments of one floor extending from the outer 55 rim of the ramp through all its ascent.

The floors 5 and 6 which extend from reaches 1 and 2 of the ramp are continuous with the ramp surface, both in its longitudinal inclination (of 4 per cent) and in its 60 transverse inclination: this to the end that

cars may run freely from ramp to floor and from floor to ramp. The 4 per cent inclination transversely of the building (in the direction B—C, O—N, A—D, M—P) need not be disturbed. The floors 5 and 6 50 may maintain this inclination. It is slight and is not disturbing in the matter of the storage of cars on the floors 5 and 6. But in the other direction, longitudinally of the building, since the inclination is greater than 75 otherwise is desirable, each floor in its further extent from the ramp outward is warped, its degree of inclination is diminished, and brought approximately to level. The floor is preferably not brought exactly 80 to level, for a certain degree of inclination is still to be desired, for purposes of drainage. The degree of inclination is, however, reduced, from that imposed by the ramp to that minimum degree sufficient for drainage 85 and no more. In Fig. I the arrows indicate inclination, and they point upward. It will then be seen that area 6 is lower and area 5 higher; that on the right-hand side, the low point is at B and that on the higher, left-hand side this low point is at D. The degree of slope is small toward the outer ends of floors 5 and 6, which there are nearly level, and the degree of slope increases inwardly, until the slope merges in the still steeper 90 banking of the ramp.

The building of such warped floors is rendered possible by the development of reinforced concrete construction.

Within the rectangle A B C D, Fig. I, 100 extend the floor spaces 7 and 8. These floor spaces, too, may correspond in inclination with the inclination of the reaches 1 and 2 of the ramp, they too may be warped from continuity with the ramp to approximate 105 level, and they, too, may constitute floor areas for the reception of and the storage of cars, but they too will slope as the arrows indicate to the common drainage.

In consequence of the development of the 110 helicoidal shape of the floor on two axes rather than on one, and in consequence of shifting of the axis along the planes D E and B F which the ascending helicoid subtends slightly before the plane D B is 115 reached (the angle which the planes D E and B F form with the plane D B may advantageously be from 20° to 30°), slight ridges are formed in the floor on the lines D E and B F, and these ridges divide the 120 otherwise continuous floor into sections. Each section has its low point, the section to the left at D, the section to the right at B. Drains are arranged at D and B, and conveniently the familiar bell traps may be set 125 at these points, a bell trap at each of these points and on each successive story. The advantages are that in washing down the floors the flood of water from an upper floor 130 5 does not sweep down a ramp portion 4 to

a lower floor 6, but gathers at D and there enters the drain. The steep portion 4 of the ramp is thus kept free of a flood which otherwise would hinder the movement of cars. Furthermore, by providing these

5 many escapes for smaller quantities of wash water, the bell traps may be looked after more effectively and kept free of obstruction, and injury to them may thus be prevented.

10 In Fig. IV the vertical line 11-12 may be understood to define the vertical plane which in Fig. I is defined by the line D-E, and the vertical line 21-22 the vertical plane of B-D, Fig. I. The point D lies in both 15 of these planes. The dotted line D-13, Fig. IV defines the slight ridge or watershed which causes the wash water which sweeps floor 5 to descend to the drain at D, rather than to pour down the ramp surface 4.

20 The variations of obliquity within the ramp afford the best disposition of surface for expedition in moving cars; the warping of the storage floors outwardly from the ramp affords freest access to the storage

25 areas and proper approximately horizontal extent of storage areas. This warping is conjointly advantageous, affording the best disposition of surface both for handling the cars and for washing the floors.

30 I claim as my invention:

In a building for the reception of vehicles a spiral ramp rising from ground level through the building, the spiral being developed on two vertical axes spaced apart, and the surface of the ramp being inclined 35 downwardly toward the axes, the change from one axis to the other in the development of the spiral occurring along a line in advance of the vertical plane common to the two axes, thus forming a watershed, the surface of the ramp extending to the walls of the building and in such extension being warped toward the horizontal and constituting storage areas.

40 In testimony whereof I have hereunto set 45 my hand.

RICHARD IRVIN.
